Inventor:

Noah Prescott

United States Patent Office.

NOAH PRESCOTT, OF DORCHESTER, MASSACHUSETTS.

Letters Patent No. 68,456, dated September 3, 1867.

IMPROVEMENT IN CLOSING BOTTLES.

The Schedule referred to in these Letters Patent and making part of the same.

TO ALL WHOM IT MAY CONCERN:

Be it known that I, NOAH PRESCOTT, of Dorchester, in the county of Norfolk, and Commonwealth of Massachusetts, have invented a new and useful Improvement in Bottle-Stoppers; and I do hereby declare that the following is a full and exact description thereof; reference being had to the accompanying drawings, and to the letters of reference marked thereon.

Figure 1 is a view of the bottle, with the stopper attached, in perspective.

Figure 2 is a view of the collar or ring in elevation.

Figure 3 is a vertical sectional view of the cap, including the stopper.

Figure 4 represents the collar or ring in plan.

Figure 5 represents in plan the stopper or cover—the cap and ring reversed.

Figure 6 is a vertical section of the cap, stopper or cover, collar or ring, and a part of the neck of the bottle, showing the protuberance or projection in the upper neck of the bottle by which the collar is kept in place.

The letters used in the different figures refer to the same parts.

To enable others skilled in the art to use my invention, I proceed to describe its construction and operation.

The cap *f* is designed to cover the upper neck and mouth of the bottle. It is constructed with an orifice, *a*, in the top, the use of which will be hereafter stated. On the inner side of the lower part there are two inclines, *e' e'*, which project inward, and which correspond and fit to two inclines, *e e*, upon the collar or ring *c*. *a* is a protuberance upon the upper neck of the bottle, designed to aid in holding the collar *c* in place. The cover or stopper *b* may be made of India rubber or other suitable material, of proper thickness to make a close joint with the bottle when the cap is on. *n* is a curved slit in the cover or stopper, cut upon such an inclination to the surface lines of the cover or stopper as to allow the part within the curve to be forced downwards, for the purpose of charging the bottle, when used for soda or mineral-water or other similar substances.

When the cap is placed upon the neck of the bottle, the inclines *e' e'* lock in with the inclines *e e*. The cap is then turned until the joint is close. A reverse movement enables the user to take the cap from the bottle.

In the drawings, the collar is constructed with a hinge upon the side, and the ends are held in place upon the opposite side of the neck of the bottle by means of a screw. It is apparent that the cap may be constructed with less material than is indicated by substituting a frame for the solid cap. It is also apparent that the stopper may be applied to fruit-cans and other similar vessels used for holding liquids or solids and preserving them from the atmospheric air.

What I claim as my invention, and desire to secure by Letters Patent, is—

The bottle-stopper for bottles, cans, and other similar vessels, constructed and applied substantially as described.

I also claim the bottle-stopper *b*, with the curved slit *n*, constructed and operating substantially as described.

NOAH PRESCOTT.
